PORTABLE TYPE TUFTING MACHINE

Edward King, Dalton, Ga.

Application January 13, 1949; Serial No. 70,615

4 Claims. (Cl. 112—80)

1

My invention relates to improvements in tufting machines of the portable type.

An important object of the invention is to provide a machine of the above mentioned type for use in making intricate tufted designs upon cloth or fabric, generally referred to as punch work.

A further object of the invention is to provide a machine of the above mentioned type having novel means to vary the length of stroke of the needle to produce tufts of varying lengths.

A further object is to provide a tufting machine which is simplified, compact and sturdy, and designed so that the working parts may be conveniently assembled, disassembled and interchanged.

Other objects and advantages of the invention will be apparent during the course of the following description.

In the accompanying drawings, forming a part of this application and in which like numerals are employed to designate like parts throughout the same,

Figure 1 is a side elevation of a machine embodying my invention, having a cover plate removed.

Figure 2 is a central vertical longitudinal section taken on line 2—2 of Figure 1, parts in elevation.

Figure 3 is a central vertical section taken on line 3—3 of Figure 2; parts broken away, the needle being shown raised.

Figure 4 is an enlarged fragmentary vertical section taken on line 4—4 of Figure 1, parts omitted, and,

Figure 5 is a side elevational view of additional eccentric elements.

In the drawings, where for the purpose of illustration is shown a preferred embodiment of my invention, the numeral 10 designates a generally rectangular housing or casing, preferably made of cast aluminum, or the like, to provide a light construction. The casing 10 is open at one side 11 to provide a main rectangular chamber or recess 12, and the opposite side 13 of the casing is provided near and above its vertical center with an outwardly projecting tubular boss 14, having a bore 15. An annular recess 16 is provided in the inner face of side 13, and surrounding the bore 15, and this recess 16 receives a ball bearing 17 or the like. Journaled within the ball bearing 17, and extending through the bore 15, and arranged horizontally is a rotatable shaft 18, having a squared end 19, projecting longitudinally outwardly of the tubular boss 14, for connection with a flexible drive shaft or cable 20.

2

The shaft 18 includes a screw threaded extension 21 extending into and substantially across the main chamber 12, Figure 2. The shaft 18 has an annular groove 22, receiving the inner end of a set screw 23, carried by the boss 14, and this arrangement prevents end play or axial movement of the shaft 18.

Mounted upon the shaft extension 21 for rotation with it is a circular eccentric element or cam 24 having an eccentrically located smooth opening 25 to slidably receive the shaft extension 21. Arranged upon opposite sides of the eccentric 24 are large flat circular clamping plates or discs 26, having their inner opposed flat faces engaging the opposite flat sides of the eccentric 24, Figure 4. The discs 26 have central smooth openings 27 to slidably receive the shaft extension 21. The opposite flat sides of the eccentric 24 and the opposed flat faces of the discs 26, which contact the eccentric, are perpendicular to the longitudinal axis of the shaft 18. Nuts 28 are mounted upon the shaft extension 21, as shown, and these nuts engage the outer faces of the discs 26, and when tightened force the discs into tight clamping engagement with the eccentric 24, so that the eccentric will rotate with the shaft 18. Rotatably mounted upon the eccentric 24 and arranged between the clamping discs 26 and spaced from these discs is an eccentric strap 29, preferably provided with a bearing or bushing 30 of bronze or similar material, and pressed tightly into the strap 29. The bushing 30 is wider than the eccentric strap 29, Figure 4, but narrower than the eccentric 24, as shown, so that the 35 clamping discs 26 engage only the opposite sides of the eccentric. The eccentric strap 29 has an integral depending tapered extension or plate 31, extending laterally of the shaft 18 and near the bottom end 32 of the casing 10. The bottom end 32 is tapered as at 33, and provided with a vertical bore 34 having its vertical axis at right angles to the axis of the shaft 18 and intersecting the same. The bore 34 is enlarged and screw threaded in its lower portion 35, for receiving the 40 upper screw threaded end of a straight cylindrical guide tube 36, secured within the screw threaded portion 35 by a nut 37. A cylindrical rod or plunger 38 is slidably mounted within the cylindrical bore of tube 36 for reciprocation, and has its upper end bifurcated for forming apertured knuckles 39 which receive the lower end of the flat plate 31 between them, and are pivotally connected to the plate 31 by a pin 40.

The guide tube 36 extends for a substantial 45 distance below the bottom end of the casing, as

shown, and is internally screw threaded near its bottom end, for receiving a screw threaded plug or needle guide 41, having a central vertical bore 42, to receive and guide a conventional hollow tufting needle 43 as the same reciprocates vertically with the plunger 38. The needle guide 41 is secured within the tube 36 by a nut 44, mounted upon the lower end of the needle guide and abutting the lower end of the tube 36, as shown. The lower end of the plunger 38 is provided with a central recess or socket 45, receiving the upper end of the needle, and the needle is secured within the socket 45 by a set screw 46, carried by the plunger. The tube 36 has a long vertical slot 47 adjacent to the thread receiving side of the tubular needle, and this slot 47 permits the passage of the thread or yarn 48 to the needle. Suitable thread guides or rings 49 are provided at one side of the casing 10, as shown, so that the yarn may be guided close to the casing as it is drawn from the spool, and it is not apt to become tangled.

Mounted upon the top end 50 of the casing 10 is a handle 51 which may be arranged horizontally, as shown, and extending laterally of the casing at right angles to the axis of the shaft 18. A flat cover plate 52 is provided for the open side of the casing, and is secured to the casing by screws 53.

In Figure 5, I have shown additional eccentrics 24', 24a, 24b and 24c. These eccentrics are identical with eccentric 24, except that the locations of their eccentric openings 25 are different in each case. This arrangement produces a different travel or throw for the eccentric strap 39 for each eccentric. A different length of stroke of the needle 43 results from the use of each of the eccentrics, and the stroke may therefore be predetermined and varied, as desired.

From the foregoing, the operation of the machine will be clear. The flexible shaft 20 drives the shaft 18 which in turn drives the eccentric 24. The eccentric rotates within the bushing 30 of the eccentric strap 29, causing the reciprocation of the plunger 38 within tube 36. Each time the plunger 38 reciprocates, the needle 43 is punched through the cloth or work W upon which the machine is being used to make a design. A loop of the yarn is pushed through the work and upon the return stroke of the plunger the needle withdraws from the work W, leaving a tuft T of yarn in its place. As the machine is moved along the work, a series of tufts is left by the operation of the needle. The lower end of the needle guide 41 is preferably rounded as at 54 to facilitate moving the machine over the work.

The length of stroke of the needle 43 is predetermined and varied according to which of the eccentrics is employed. Although I have shown five eccentrics to produce five variations in the length of stroke of the needle, it is to be understood that any number of eccentrics may be employed having their eccentric openings located at any desired point.

In changing the eccentric 24, the outer nut 28 is unscrewed from the shaft extension 21, and the machine may be held with its open side down. Since outer disc 26 has no screw threaded engagement with the shaft extension 21, it may be readily removed from the shaft extension, or may drop therefrom. The eccentric also has no screw threaded engagement with the shaft extension 21, and will drop out of the bushing 30, or may be readily removed therefrom, the bushing 30

remaining within the eccentric strap 29. Another eccentric having a different throw is placed upon the shaft extension 21, and passed into the bushing 30. The outer disc 26 is placed upon the shaft extension 21, and the outer nut 28 mounted upon the shaft extension. This nut 28 is tightened to rigidly clamp the eccentric between the discs 26, and these discs are rigidly clamped against the adjacent nuts. It is thus seen that the eccentric is rigidly secured to the shaft extension 21, for rotation therewith, and may quickly and conveniently be separated therefrom, as explained.

It is to be understood that the form of the invention herewith shown and described is to be taken as a preferred example of the same, and that various changes in the shape, size and arrangement of parts may be resorted to without departing from the spirit of the invention or the scope of the subjoined claims.

Having thus described the invention, I claim:

1. A tufting machine, comprising a portable support, a shaft carried by the support, an eccentric having an opening removably receiving the shaft so that the eccentric may be removed from the shaft by an axial movement of the eccentric, said opening having a substantially close fit upon the shaft and concentric with the shaft so that the eccentric cannot be shifted perceptibly transversely of the shaft, said eccentric having a periphery which is free from a groove, clamping elements carried by the shaft and arranged upon opposite sides of the eccentric to engage therewith, one clamping element being removable from the shaft, means carried by the shaft to bring the clamping elements into clamping engagement with the eccentric and permit of the removal of one clamping element, a guide carried by the support, a plunger mounted to reciprocate within the guide, an eccentric strap having a connecting part secured to the plunger, said eccentric strap having an opening to receive the periphery of the eccentric, the eccentric being removable from the opening of the eccentric strap by an axial movement of the eccentric while the strap remains secured to the plunger, and tufting means including a needle secured to the plunger.

2. A tufting machine, comprising a portable support, a shaft carried by the support and having a screw threaded portion, a clamping element mounted upon the shaft, an eccentric having an opening removably receiving the shaft and free from screw threaded engagement with the shaft and arranged upon one side of the clamping element and removable from the shaft by an axial movement of the eccentric, said opening having a substantially close fit upon the shaft and concentric with the shaft so that the eccentric cannot be shifted perceptibly transversely of the shaft, said eccentric having a periphery which is free from a groove, a second clamping element having an opening to removably receive the shaft and free from screw threaded engagement therewith, a nut having screw threaded engagement with the shaft and engaging the second clamping element to effect a relative axial movement between the clamping elements, guide means carried by the support, a plunger to reciprocate within the guide means, an eccentric strap having a connecting part secured to the plunger and being arranged between the clamping elements, said connecting strap having an opening to receive the periphery of the eccentric, the eccentric being removable from the opening

of the eccentric strap by an axial movement of the eccentric while the strap remains secured to the plunger, and tufting means including a needle secured to the plunger.

3. A tufting machine, comprising a portable support, a shaft carried by the support, a clamping disc mounted upon the shaft, an eccentric having an opening removably receiving the shaft so that the eccentric may be removed from the shaft by an axial movement of the eccentric, said opening having a substantially close fit upon the shaft and concentric with the shaft so that the eccentric cannot be shifted perceptibly transversely of the shaft, said eccentric having a periphery which is free from a groove, the eccentric having the clamping disc disposed upon one side thereof, a second clamping disc having an opening to removably receive the shaft and disposed upon the opposite side of the eccentric, means carried by the shaft to effect a relative axial movement between the clamping discs to rigidly secure them to the eccentric, guide means carried by the support, a plunger to reciprocate within the guide means, an eccentric strap having a connecting part secured to the plunger, said eccentric strap being arranged between the clamping discs and having an opening to receive the periphery of the eccentric, the eccentric being removable from the opening of the eccentric strap by an axial movement of the eccentric while the strap remains secured to the plunger, the clamping discs projecting radially beyond the eccentric and the eccentric strap being narrower than the eccentric, and tufting means including a needle secured to the plunger.

4. A tufting machine, comprising a casing having an opening in one side, a transverse shaft mounted upon the casing and having its free end arranged adjacent to the opening, a clamping element mounted upon the shaft within the casing remote from the free end of the shaft, an

eccentric having an opening removably receiving the shaft so that the eccentric may be removed from the shaft and through the opening in the casing by an axial movement of the eccentric, said opening having a substantially close fit upon the shaft and concentric with the shaft so that the eccentric cannot be shifted perceptibly transversely of the shaft, the eccentric having the clamping element engaging its side remote from the free end of the shaft, said eccentric having a periphery which is free from a groove, a second clamping element to engage with the opposite side of the eccentric and having an opening to removably receive the shaft, a nut having screw threaded engagement with the free end of the shaft to bear against the second clamping element, a guide tube secured to the casing, a plunger to reciprocate within the guide tube, an eccentric strap having a connecting part secured to the plunger, said eccentric strap having an opening to receive the periphery of the eccentric, the eccentric being removable from the opening of the eccentric strap by an axial movement of the eccentric while the strap remains secured to the plunger, a needle guide carried by the guide tube, and a needle secured to the plunger.
